99,361

DESIGN FOR A GRATER OR SIMILAR ARTICLE

William Moran, Woodside, N. Y.

Application January 17, 1936, Serial No. 60,638

Term of patent 3½ years

To all whom it may concern:

Be it known that I, William Moran, a citizen of the United States, residing at Woodside, Long Island, in the county of Queens and State of New York, have invented a new, original, and ornamental Design for a Grater or Similar Article, of which the following is a specification, reference being had to the accompanying drawing, forming a part thereof.

Fig. 1 is a top plan view of a grater or similar article, showing my new design.

Fig. 2 is a sectional view of the same taken on the line 2—2 of Fig. 1.

I claim:

The ornamental design for a grater or similar article, as shown.

In testimony whereof I have affixed my signature.

WILLIAM MORAN.
